UNITED STATES PATENT OFFICE.

AARON WENGER, OF BAYONNE, NEW JERSEY.

PHONOGRAPH-RECORD HOLDER.

1,415,749.

Specification of Letters Patent.

Patented May 9, 1922.

Application filed November 16, 1921. Serial No. 515,634.

To all whom it may concern:

Be it known that I, AARON WENGER, a citizen of the United States, and a resident of Bayonne, in the county of Hudson and 5 State of New Jersey, have invented a new and Improved Phonograph-Record Holder, of which the following is a full, clear, and exact description.

This invention relates to holders for 10 phonograph disc records and contemplates a means for supporting and indexing records within a record cabinet or housing whereby to facilitate the storing, removal, and locating of the desired record in a minimum 15 of time.

Heretofore records are either haphazardly stored in the record cabinet or are arranged in filing books, requiring that the operator withdraw the book from the cabinet, consult 20 the index, remove the record, return the record to its proper envelop, and replace the book in the cabinet.

To eliminate the time incident to these 25 operations and the trouble necessitated in indexing the records, a simple and inexpensive pivoted supporting arm has been provided which includes a manipulating handle upon which an indicating card bearing the name of the record is mounted whereby the 30 operator may immediately locate and remove the desired record and return the same to its proper place.

With the above recited and other objects 35 in view, the invention resides in the novel construction set forth in the following specification, particularly pointed out in the appended claims and illustrated in the accompanying drawings, it being understood that the right is reserved to embodiments other 40 than those actually illustrated herein to the full extent indicated by the general meaning of the terms in which the claims are expressed.

In the drawings—

45 Figure 1 is a front elevation of a record cabinet equipped with the record holding means, parts being broken away to disclose the underlying structure.

Fig. 2 is a sectional plan view taken approximately on the line 2—2 of Fig. 1.

Fig. 3 is a fragmentary sectional view taken on the line 3—3 of Fig. 2.

Fig. 4 is a similar view taken at the lower corner of the cabinet.

55 Fig. 5 is a fragmentary sectional view

taken approximately on the line 5—5 of Fig. 2.

Fig. 6 is a detail fragmentary bottom plan view of the outer end of the supporting arm.

Fig. 7 is a detail fragmentary perspective 60 view of the inner end of the arm.

Referring to the drawings by characters of reference, 10 designates a record cabinet provided with the usual door 11 for closing the same. The means for supporting and 65 projecting the records into and out of the cabinet when the door is opened comprises a plurality of supporting arms 13 mounted on a common pivot rod 14 arranged vertically within the cabinet at one corner thereof adjacent the open front thereof. The arms are spaced apart and guided to swing horizontally by a plate 15 of substantially U-shaped formation in cross section which is secured to the side wall of the cabinet and embraces 70 the rod 14. The plate 15 is provided with horizontally and equi-distantly spaced slits 16 through which the inner perforated ends of the arms extend and receive the rod 14. The inner pivoted ends of the arms 13 are 75 provided with angularly disposed extensions 16, the free terminals of which are bent at an angle to provide finger manipulating portions 17. The extensions 16 are provided with retaining lugs 18 adjacent their lower 80 edges which are designed to coact with an index card 19 upon which the name of the record supported by the arm is inscribed. Preferably the extensions 16 constitute an integral part of the arm which is bent to 85 occupy a vertical plane or a plane at substantially right angles to the plane of the arm. The outer free end of the arm 13 is longitudinally slotted as at 20 and provided on its under side with an enlarged recess 21 90 communicating with the slot 20, said slot 20 and recess 21 being of gradually increasing widths from the outer ends toward the centers thereof. A rotary supporting table or 95 disk 22 is mounted for rotation and longitudinal sliding movement on the upper surface of the arm 13 by means of a headed stud 23, the shank of which extends through the slot 20 and the head of which is accommodated by a recess 21. The shank is thread- 100edly engaged as at 24 in the table or disk 22 and is provided with an upstanding extremity 25 which is designed to be received by the center opening 26 of a disk record 27. By this arrangement the records are 105

110

supported by the arms 13 for horizontal swinging movement to effect their positioning within the cabinet or projection therefrom, use being made of the extensions 16 5 to swing the arms.

In use and operation of the device the operator, by manipulating the portions 17 of the arm with the finger, using the index cards 19 as a guide, may selectively swing 10 the arm and the desired record exteriorly of the cabinet where it may be readily lifted from the table or disk 22 and placed on the phonograph. In swinging the arm, to project the record from the cabinet, should the 15 record be of a size which will cause the peripheral edge thereof to contact with the side of the doorway of the cabinet, the slideable mounting will accommodate and permit of relative movement between the record and 20 the supporting arm. When the record is returned to its position, the centrifugal force set up by the swinging action will tend to throw the record toward the outer end of the supporting arm, the outward movement 25 being arrested by the arrival of the stud 23 at the outer end of its slot. It will thus be seen that a simple, safe and effective means for the handling and storing of graphophone disk records has been provided whereby the 30 records may be expeditiously selected and returned to the cabinet when desired.

I claim:

1. The combination with a graphophone record cabinet, of means for normally supporting the records in superposed relation within the cabinet, said means including members mounted for horizontal swinging movement to project the record from the cabinet or position the same therein, and 35 elements carried by said members, said elements being connected therewith for rotary and sliding movements.

2. The combination with a graphophone record cabinet, of means for normally supporting the records in superposed relation 40 within the cabinet, said means being mounted for horizontal swinging movement to project the record from the cabinet or position the same therein, said means comprising 45 arms having their free ends slotted, a table supported by each arm and a trunnion extending through the table and received by the slotted portion of the arm to permit of 50 rotary and sliding movements of the table 55 on the arm.

3. The combination with a record cabinet, of means for rotatably and slidably supporting the records in superposed relation within the cabinet, comprising superposed arms, tables rotatably and slidably mounted on 60 said arms at one extremity, and means for pivotally associating the opposite extremities of the arms for horizontal swinging movements whereby to effect the projection of the records from or positioning of the same 65 within said cabinet.

4. The combination with a phonograph record cabinet, of means for handling and supporting the records to permit of the projection from or positioning of the same 70 within the cabinet comprising a plurality of superposed arms a vertically disposed U-shaped plate secured to one side of the doorway, said plate having spaced horizontal slits for respectively receiving one end of 75 each arm, a rod extending through said plate and said ends of the arms for pivoting the same for horizontal swinging movement, and angularly disposed manipulating extensions 80 adjacent the pivoted ends of the arms adapted to support record indexing indicia.

5. The combination with a phonograph record cabinet, of means for handling and supporting the records to permit of the projection from or positioning of the same with 85 in the cabinet comprising a plurality of superposed arms pivoted adjacent one side of the doorway for horizontal swinging movement, a record supporting member mounted 90 on the free end of the arm for relative longitudinal and sliding movements with respect thereto, and an angularly disposed manipulating extension adjacent the pivoted end of the arm.

6. The combination with a phonograph record cabinet, of means for handling and supporting the records to permit of the projection from or positioning of the same with 95 in the cabinet comprising a plurality of superposed arms pivoted adjacent one side 100 of the doorway for horizontal swinging movement, a record supporting member mounted on the free end of the arm for relative longitudinal and sliding movements 105 with respect thereto, an angularly disposed manipulating extension adjacent the pivoted end of the arm, and means carried by said extension whereby an index card may be associated therewith.

AARON WENGER.
